(57) **CLAIM**

The ornamental design for a combined foldable leg support and support board for grill, as shown and described.

DESCRIPTION

FIG. 1 is a perspective view of a combined foldable leg support and support board for grill of my new ornamental design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof in a sample environmental setting.

The broken line elements in FIG. 7 form no part of the claimed design and act as a boundaries of the claimed design. All other broken lines depict environment and form no part of the claimed design.
